UNITED STATES PATENT OFFICE.

JOHN E. SEDERHOLM, OF ST. PAUL, MINNESOTA, ASSIGNOR TO AMERICAN HOIST & DERRICK COMPANY, OF ST. PAUL, MINNESOTA, A PARTNERSHIP, COMPOSED OF OLIVER CROSBY, T. J. JOHNSON AND W. O. WASBURN.

LIFTING MAGNET.

Application filed January 7, 1922. Serial No. 527,679.

To all whom it may concern:

Be it known that I, JOHN E. SEDERHOLM, a citizen of the United States, resident of St. Paul, in the county of Ramsey and State of Minnesota, have invented certain new and useful Improvements in Lifting Magnets, of which the following is a specification.

This invention relates to improvements 10 in magnets designed for picking up and moving from one place to another articles of iron or steel.

The principal object of my invention is to provide a lifting magnet having its winding divided or split up into a plurality of sections, making it possible to change the voltage of the current employed without re-winding the magnet.

Another object of the invention is to 20 provide for the operation of a lifting magnet with currents of high voltages without the employment of external resistance in the main circuit, as usually employed at the present time.

25 Other objects of the invention will appear from the following detailed description taken in connection with the accompanying drawings in which,

Figure 1 is a perspective view of a lifting magnet embodying my invention;

Figure 2 is a transverse vertical section on line 2—2 of Figure 3, looking in the direction of the arrow;

Figure 3 is a horizontal section on line 3—3 of Figure 2 looking in the direction of the arrow, the coils being shown connected in series;

Figure 4 is a detail plan view of the terminal box and a portion of the lifting 40 magnet, the coils being shown connected in parallel;

Figure 5 is a detail section of the magnet shell, or case, looking from below, and showing a portion of the coils, and the 45 means for holding the same in place in the shell.

In the drawings, 1 represents the magnet casing preferably formed of a single sheet 50 of casting of circular form, this casting constituting the magnetic circuit of the magnet. The outer surface of the magnet casing is preferably formed with a series of ribs 2 to increase the heat radiating surface. The top of the casing is preferably

provided with a series of lugs 3, 3, to 55 which lifting chains 4 are connected by suitable pins 5. These chains are preferably three in number, and they are connected to a ring 6, which may be engaged by a hook 7, upon a suitable lifting chain. 60 The casing 1 is preferably provided at its lower edge with the outwardly extending flange 8. The casing 1 is also provided with an annular recess 9 opening through 65 the bottom of the casing. I provide within the annular recess 9 a plurality of coils or windings. I have here shown two such coils, the inner being designated 10 and the outer 11. These coils are spaced apart and are held in position in said recess by 70 a series of straps 12, extending across the under side of the coils and secured in position by bolts 13, that extend through said straps and pass upward between the coils and are screwed into threaded recesses 14 75 in the upper part of the casing (Figure 2). A non-magnetic coil shield plate 15, preferably provided upon its upper surface with a rubber gasket 16, is seated in shouldered recesses 17, 17, in the bottom of the 80 casing surrounding the annular recess 9 (Figure 2).

An outer annular pole shoe 18 is secured to the bottom of the casing, outside of the annular recess, by bolts 19, and this shoe 85 is preferably arranged to project inwardly a short distance beyond the wall of the recess so as to engage the outer edge of the non-magnetic coil shield plate 15. (Figure 2). The center of the casing 1 is preferably provided with a ventilating opening 20. An inner circular pole shoe 21, having preferably a central ventilating opening 22, coinciding with the opening 20 in the casing, is secured to the casing by 90 suitable bolts 23, that pass through openings 24 in said pole shoe and corresponding opening 25 in the casing.

The heads of the bolts 19 and 23 are 100 preferably arranged in countersunk recesses in the pole shoes so as to leave said shoes with smooth under surfaces.

The pole shoe 21 preferably projects slightly beyond the inner wall of the recess 9, thereby engaging the nonmagnetic coil shield plate 15, and holding this edge of the plate in position over the recess (Figure 2). An opening is formed through the top wall

of the casing (Figures 2, 3 and 4), and this opening forms a terminal box 26 through which connections may be made with the coils 10 and 11 within the casing. The terminal box 26 is provided with a suitable cover 27 secured in position by bolts 28, and it has lugs 29 through which extend the connecting pins 30 to which the electric conductors 31, 31, are attached. I provide suitable connectors 32 between the pins 30 and the coil terminals 30^a, and also one or more connectors 33 connecting said coils.

I may connect said coils in series, as illustrated in Figures 2 and 3 of the drawings, or I may connect them in parallel as illustrated in Figure 4.

The terminal box cover 27 is preferably provided with an opening 34 arranged to be closed by a threaded plug 35 (Figures 1 and 2). After the parts are assembled, in the manner described, the entire space within the recess surrounding and below the coils may be filled with pitch, 36, or other suitable material, that is melted and run in through the opening in the cover of the terminal box.

While I have shown but two coils arranged within the recess in the casing a greater number of coils may be employed if desired.

By employing a plurality of coils, thereby splitting the winding of the magnet up into two or more sections, it is possible to change the voltage of the magnet without re-winding the coil. The magnet may also be operated on high voltages without using external resistance in the main circuit as is usually done at the present time. With this arrangement it is possible to put a discharge resistance across each section of winding, each section being connected to the controller.

The high inductive potential set up when the circuit of the lifting magnet is broken, due to the great mass of iron surrounding the coils, is, with my invention, divided up between the coils in my new design, making the breaking down strain $\frac{1}{2}$, $\frac{1}{3}$, or $\frac{1}{4}$ of the magnet using only one coil.

With this construction better ventilation is secured thus increasing the lifting capacity of the magnet without increasing its own weight.

With a duplex, triplex, or quadruplex construction of coils, a row of bolts should be inserted between each pair of sections of coils, with a suitable strap of non-magnetic material extending across all of the coils. This makes a very rugged and firm construction. Metallic spools such as have heretofore been used are done away with, as such spools make a magnet sluggish and tend to increase the temperature through eddy currents generated in the spool.

I do not limit myself to the use of two coils in the casing, as a greater number may be employed without departing from my invention, nor do I limit myself to the details of the construction herein disclosed as the same may be varied in many particulars without departing from my invention.

I claim as my invention:

1. In a device of the class described, the combination, with a circular, metallic magnet case, having an annular recess formed in one face thereof, of a plurality of concentric coils arranged in said recess, an annular ring of insulating material between the coils, bolts passing up through said material into said casing with means thereon to retain the coils in said recess, means connecting said coils in series or in parallel, and inner and outer removable pole shoes secured upon the lower face of said case.

2. In a device of the class described, the combination, with a circular metallic magnet case having an annular recess formed in one face thereof, of a plurality of concentric coils arranged in said recess, and a series of straps extending across said coils and below the same, bolts passing through said straps and between said coils and engaging openings in the upper wall of said case.

In witness whereof, I have hereunto set my hand this 31st day of December, 1921.

JOHN E. SEDERHOLM.
